UNITED STATES PATENT OFFICE

CONSTANT VANHORN, OF SENTINEL BUTTE, NORTH DAKOTA

ADJUSTABLE FOLDING SCAFFOLD

Application filed April 27, 1932. Serial No. 607,823.

This invention relates to a scaffold primarily adapted to be constructed of metal and to be of the folding or knock-down type as well as adjustable.

It is particularly aimed to provide a structure in which the brace means for the horizontal supporting bar are operable with novel vertical elements.

The more specific objects and advantages will become apparent from a consideration of the description following taken in connection with accompanying drawings, illustrating an operative embodiment.

In said drawings:—

Figure 1 is an end elevation of the scaffold,

Figure 2 is a side elevation of half of the scaffold,

Figure 3 is a vertical sectional view taken on the line 3—3 of Figure 2,

Figure 4 is a horizontal sectional view taken on the line 4—4 of Figure 1,

Figure 5 is a horizontal sectional view taken on the line 5—5 of Figure 1,

Figure 6 is a vertical sectional view taken on the line 6—6 of Figure 1, and

Figure 7 is a vertical sectional view taken on the line 7—7 of Figure 2.

The scaffold has a supporting device A at each end thereof, one of such devices alone being shown since the other is a duplicate thereof. Such supporting device comprises diagonally disposed legs 10 of angle or equivalent construction connected at the top by breast plates 11 and bolts 12 removably and detachably passed therethrough, the lowermost bolts 12 having nuts 13 equipped with integral handles 14 so that they may be quickly applied or removed. A central leg or upright 15 is secured between the breast plates 11 and a cross bar 16 crosses the legs 10 and 15, and is removable therefrom so that in the absence of the lower bolts 12 the bar 16 may be removed and the legs 10 swung into parallelism with the leg 15. A bolt 17 detachably connects the cross bar 16 to the leg 15 and bolts 18 detachably connect the cross bar to the legs 10, the nuts 19 therefor preferably having handles 20 integral therewith. A supporting bar 21 is

vertically adjustable in the channel of the leg 15, having rack teeth 22 in mesh with the teeth of a pinion 23 keyed to a stub shaft 24 journaled in the plates 11 and to which an operating handle or crank 25 is fastened. Said shaft 24 also has a ratchet wheel 26 keyed thereto which coacts with a pawl 27 pivoted at 28 to one of the plates 11.

The supporting bars 21 are stepped or cut away at the top as at 29 so that a scaffold stage supporting bar 30 may be detachably supported on and connected to the bars 21, of adjacent pairs of the supporting devices A. Clamping bolts 31 of L-shape secure the bars 30 in place and nuts 32, having handles 33 thereon, serve to tighten the clamps 31.

Braces 34 are provided between the elements 30 and bars 21, the same being pivotally connected as at 35 to the latter, and extending through the channel of the leg 15. As best detailed in Figures 2 and 7, the upper end of the braces 34 are angularly disposed as at 36 and stepped or shouldered as at 37 to accommodate the bars 30, rigid attachment being had with the latter by means of angle or clamp bolts 38 and coacting nuts 39 therefor preferably provided with handles 40. It will be noted that the braces 34 are of angle form in cross section so that when the device is disassembled, and the member 30 is not too long, it may be compactly disposed within the space or angle.

Various changes may be resorted to provided they fall within the spirit and scope of the appended claims.

What I claim as my invention is:—

1. A device of the class described comprising angularly disposed legs, a breast plate connecting the legs, a vertical leg between the first mentioned legs, a cross bar connecting all of the said legs, said vertical leg being of channel form, a lifting bar slideable in the channel of the last mentioned leg and provided with rack teeth, a pinion in mesh with the rack teeth, a shaft journaled on the breast plate mounting said pinion, a ratchet wheel on said shaft, and a pawl coacting with said ratchet wheel.

2. A device of the class described com-

prising angularly disposed legs, a breast plate pivotally mounting the legs, driven fastenings engaging the legs and breast plate and holding them angularly disposed, 5 said fastenings being removable whereby the legs may be moved into folded position, a vertical leg between the first mentioned legs, a cross bar connecting all of said legs, said vertical leg being of channel form, a lifting 10 bar slidable in the channel of the last mentioned leg and provided with rack teeth, a pinion in mesh with the rack teeth, a shaft journaled on the breast plate mounting said pinion, a ratchet wheel on said shaft, and a 15 pawl coacting with said ratchet wheel.

3. A device of the class described comprising angularly disposed legs, a breast plate connecting the legs, a vertical leg between the first mentioned legs, a cross bar 20 connecting all of said legs, said vertical leg being of channel form, a lifting bar slidable in the channel of the last mentioned leg and provided with rack teeth, a pinion in mesh with the rack teeth, a shaft journaled on the 25 breast plate mounting said pinion, a ratchet wheel on said shaft, a pawl coacting with said ratchet wheel, said lifting bar being provided with means to secure it to a scaffold stage supporting element, a brace pivotally connected to the lifting bar, and means on the brace for connection to the element supported by the lifting bar.

4. A device of the class described comprising a breast plate, diagonal legs pivoted thereto, fastenings engaging the legs and breast plate and preventing pivotal movement of the legs, a channel leg intermediate the first mentioned legs, a bar pivoted to the channel leg and detachably connected to the 40 first mentioned legs, a lifting bar operable in the channel of the channel leg and provided with rack teeth, a pinion engaging said rack teeth, a shaft on the breast plate to which the pinion is keyed, a ratchet wheel 45 on said shaft, a pawl on said breast plate coacting with the ratchet wheel, said lifting bar being provided with means to secure it to a scaffold stage supporting element, and a brace pivotally connected to the lifting 50 bar and engageable with the same element as the lifting bar.

5. A device of the class described comprising a breast plate, diagonal legs pivoted thereto, fastenings engaging the legs and breast plate and preventing pivotal movement of the legs, a channel leg intermediate the first mentioned legs, a bar pivoted to the channel leg and detachably connected to the first mentioned legs, a lifting bar operable 60 in the channel of the channel leg and provided with rack teeth, a pinion engaging said rack teeth, a shaft on the breast plate to which the pinion is keyed, a ratchet wheel 65 on said shaft, a pawl on said breast plate coacting with the ratchet wheel, said lifting

bar being provided with means to secure it to a scaffold stage supporting element, a brace pivotally connected to the lifting bar and engageable with the same element as the lifting bar, said lifting bar and brace having stepped portions for engagement by a supported article, and clamping means for securing the supported article in the stepped portions.

In testimony whereof I affix my signature. 75
CONSTANT VANHORN.
